UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed March 20, 1925. Serial No. 17,047.

To all whom it may concern:

Be it known that I, HARRY A. DAVIS, a citizen of the United States, and a resident of Hopedale, in the county of Worcester and 5 State of Massachusetts, have invented an Improvement in Feeler Mechanisms for Looms, of which the following description, in connection with the accompanying drawings, is a specification, like characters on the 10 drawings representing like parts.

This invention relates to feeler mechanisms for looms, and more particularly to intermittent feeler mechanisms wherein the feeler has periods of activity and inactivity 15 during weaving with the same supply of filling in the shuttle.

In feeler mechanisms of this general type, the feeler is held in a frontward position during its periods of inactivity and released 20 at intervals to its periods of activity, and should the feeler during a period of activity find a working supply of filling in the shuttle on a detecting beat it is returned into control of means for holding the feeler 25 in its frontward position during a subsequent period of inactivity. When the feeler is moved frontwardly by a working supply of filling during a period of activity it will sometimes fail to engage the means or 30 detent for holding it in its frontward inactive position, and at such times should the said means or detent be moved further frontward, the feeler will, on subsequent detecting beats, remain in action and not be returned to its position of inactivity, with the 35 result that the constant recurring contacts of the feeler with the filling during such period of activity is liable to injure the filling.

40 One of the objects of the present invention is to provide a feeler mechanism of the intermittent or suspended actuation type, wherein the means for controlling the active and inactive periods of the feeler is constituted by two independent mechanisms 45 which act successively at times to release the feeler and after a predetermined number of detecting beats to withdraw or move the feeler frontwardly beyond the reach of the filling.

Another important feature of the invention consists in means for varying the intervals between the successive action of the two controlling mechanisms, so that the

feeler may remain active for two or more 55 detecting beats or until it has been engaged by the feeler holding means or detent, and then be moved frontwardly beyond the reach of the filling. This feature of the invention enables the feeler controlling 60 mechanisms to be so related as to their respective intervals of operation as to insure that before the feeler holding means or detent is moved frontwardly, the feeler shall be engaged thereby. 65

The above features of the present invention and other novel combination of parts will best be made clear from the following description and the accompanying drawings of one good form thereof. 70

In the drawings:

Fig. 1 is a perspective view of a loom provided with the present invention;

Fig. 2 is a side elevation on an enlarged scale showing a feeler mechanism provided 75 with the present invention, the feeler being in its withdrawn position;

Fig. 3 is an enlarged detail showing portions of the feeler mechanism, some of the parts being shown in section; and 80

Fig. 4 is a front elevation showing the successive action of the feeler controlling mechanism and the devices whereby such successive action is attained. 85

The feeler mechanism of the present invention may be utilized to change the operation of the loom on the detection of substantial exhaustion of the filling in the shuttle, and such change in the operation of the loom in the present illustration is shown as 90 effecting replenishment of filling, which may be brought about either by changing the filling carrier in the shuttle or by changing the shuttle itself. The filling replenishing mechanism is not herein shown and described, because the details thereof form no part of the present invention and may be of any usual or desired character. 95

The two feeler controlling mechanisms which form a feature of the present invention are herein shown as operated from parts connected with the take-up, and such operation of the two mechanisms is preferred although such mechanisms may be operated from any going part of the loom. 100

The loom frame 1 may be of any usual or desired character and it has mounted in suitable bearings 2, as shown, the usual trans-

verse or rock shaft 3 which has secured to it an upstanding arm 4 to which is pivotally connected at 5 the actuator 6, the rear end portion of which is provided with a pivoted member 7 connected to the actuator by the pivot 8. The rear end portion of the member 7 is adapted to be engaged at times by a cam follower 9 or a part actuated thereby, and under such conditions the actuator 6 will be moved frontwardly and effect a change in the loom operation, such as replenishing the filling, as now well understood in the art.

Pivots mounted at 10 upon a support 11 conveniently secured to the shipper stand 12 is a bell crank lever, one arm 13 of which underlies a finger 14 secured to the member 7. The other arm 15 of the bell crank or other lever is connected to a transmitter 16 secured to a slide 17 which is under the control of the feeler.

The feeler stand 18 is adjustably connected to the shipper stand by a bolt 19, and at its rear portion the feeler stand 18 has a guideway 20 for the slide 17, through which the feeler 21 extends. The frontwardly extending stem portion 22 of the feeler passes through a bearing 23 at the front of the feeler stand, and between the bearing 23 and the bridge or support 24, secured to the feeler, is a spring 25 normally tending to move the feeler into rearward feeling position. The parts so far described are or may be substantially the same as shown and described in the patent to Edward S. Stimpson, No. 1,309,226, July 8, 1919, and need no further description.

The lay 26 may be of usual type, provided with a shuttle box 27, the front wall of which has an opening 28 which registers with a similar opening 29 in the front wall of the shuttle 30 when the latter is in the detecting box, the construction being such that on a detecting beat the feeler 21 may enter the shuttle 30 and feel for the filling therein. The construction last described is likewise shown in the Stimpson patent referred to.

Mounted adjacent to the feeler stand 18 is a support or bracket on which certain parts of the feeler mechanism to be described are mounted. As shown in the present instance of the invention, such support comprises a bracket, the front wall of which extends transversely of the feeler stand 18 as at 31, and the side portion 32 of which extends along the side of the feeler stand, and is provided with an overhang or flange 33 having openings for bolts 34 by which the bracket may be secured to the feeler stand or other convenient support. The bracket just described may be conveniently mounted upon the feeler stand for adjustment by means of a thumb screw 35, but this may not always be necessary.

Pivots mounted by a vertical axis 36 on the part 31 of the bracket is a detent carrier 37 which consequently has a swinging movement towards and from the front of the loom, and is normally under the influence of a spring 38 interposed between the carrier 37 and a projection 39 of the bracket, tending to swing the detent carrier into a rearward position.

Pivots mounted on the detent carrier 37 at 40 is the detent 41, the pivotal mounting of the detent on the carrier being such that the detent moves about the horizontal axis. In the construction shown, the detent carrier 37 has the slot or opening 42 in which the detent may have its pivotal movement, one end of the detent, as indicated in Fig. 3, being normally under the influence of a spring 43 tending to move the detent into its feeler engaging position. The frontwardly extending stem 22 of the feeler is provided with a collar or shoulder 44, as shown in Fig. 2, rearwardly of which the active end of the detent 41 is adapted to engage when the feeler is moved frontwardly by a working supply of filling in the shuttle on a detecting beat.

The present invention contemplates that when the feeler has been released to a period of activity and is moved frontwardly by a working supply of filling in the shuttle that the detent 41 shall engage rearwardly of the projection or collar 44 on the feeler and prevent rearward movement thereof, and that when so engaged, the detent carrier 37 shall be moved frontwardly to withdraw the feeler to a further frontward position out of reach of the filling on detecting beats, and that when so moved frontwardly the detent carrier will be held in its feeler holding position by a catch or latch, until when the feeler is tripped to its period of activity, the latch will also be tripped to permit the feeler carrier to respond to the demands of the spring 38 and move rearwardly for re-engagement with the feeler when the latter is again moved frontwardly by a working supply of filling.

In accordance with the present invention, means is provided for moving the detent carrier 37 frontwardly about its vertical axis 36 when the feeler has been engaged by the detent. As shown in the present instance of the invention, such controlling mechanism consists of a cam 45 mounted on or formed integral with the detent carrier 37, as more clearly indicated in Figs. 1 and 2, and an arm which by engagement with said cam effects frontward movement of the detent carrier. In the present instance, the arm 46 is pivotally mounted at 47 on the bracket 32, Fig. 2, and is normally under the influence of a spring 48 tending to hold the arm 46 in its full line position, Fig. 2, but movable, as will hereinafter be de-

scribed, to its dotted line position, Fig. 2, to move the detent carrier forwardly.

Pivottally mounted at 49 on the bracket 32 is a latch 50 having a shoulder 51 which is adapted to engage rearwardly of the detent carrier 37 when the detent carrier is moved to its forward position, and overlying the detent is a projection 52 on the latch, such that should the detent be moved on the detent carrier to effect release of the feeler, such movement will effect a trip of the latch and permit the detent carrier to move rearwardly following a release of the feeler. The spring 48 is herein shown as utilized to effect latching engagement of the latch with the detent carrier, but a separate spring may be employed for this purpose if desired.

The detent carrier has an enlarged portion 53 into which extends the sheathed wire 54, the end of the wire normally resting against the under portion of the inactive end of the detent, the construction being such that should the flexible wire be moved longitudinally in its sheath 55, the detent will be actuated to release the feeler and also disengage the latch from the detent carrier, whereupon the detent carrier will be moved rearwardly by the spring 38.

The bracket 32, as shown, is provided with an enlargement 56 into an opening of which extends the sheathed wire 57 which normally bears on the under side of the active end of the arm 46, Fig. 2, the construction being such that should the sheathed wire 57 be moved longitudinally in its sheath 58, the arm 46 will be moved from its full to its dotted line position, Fig. 2, to thereby act upon the cam 45 and move the detent carrier and detent forwardly, whereupon the latch 50 will engage rearwardly of the detent carrier and hold it in its forward position, while the projection 52 of the latch will overlie the inactive end of the detent 41.

From the mechanism thus far described it will be apparent that the present construction provides two independent controlling mechanisms for the feeler, one to periodically release the feeler to its periods of activity, and the other to move the feeler forwardly when, following its release, it is moved forwardly by a working supply of filling in the shuttle on a detecting beat and engaged with the detent.

Under some conditions in loom operation, the feeler may fail to be engaged by the detent when during its active period it is moved forwardly on a detecting beat, and at such times of non-engagement of the detent with the feeler, should the detent carrier be moved forwardly, the feeler will remain active. The two controller mechanisms of the feeler, therefore, are arranged for actuation independently from

a going part of the loom and are contrived to act in desired succession, first, to release the feeler to its periods of activity, and then after a predetermined number of detecting beats when the feeler has been engaged by the detent, to move the feeler forwardly beyond the reach of the filling. As shown in the present instance, such independent control of the feeler is actuated from the take-up, but the same results may be secured from any other going part of the loom.

The take-up mechanism may be of any usual type, and as shown, consists of the pick wheel 59 and a train of transmission gearing 60, 61, 62 and 63, extending to the usual take-up or sand roll. The pick wheel 59, in the present instance, is shown as provided with separate actuators for each of the sheathed wires 54 and 57, the ends of which are supported in suitable recesses in a bracket or plate 64 secured to the loom frame. The bracket 64 is provided with a stud 65 on which is pivotally supported the rocker 66 for moving the sheathed wire 54, and the independent rocker 67 for moving the sheathed wire 57. Mounted on or secured to the pick wheel 59 is a plate 68 having an actuator or lug 69 for actuating the rocker 66 as the pick wheel is rotated step by step. The actuation of the rocker 66 trips the detent from the feeler and releases the latch from the detent carrier, as hereinbefore described.

The plate 68 may be secured to the pick wheel in any approved manner as by the bolt 69', as indicated in Fig. 4. Secured to or mounted on the pick wheel 59 is a second plate 70 having a lug or actuator 71 to act upon the rocker 67 which effects movement of the sheathed wire 57, as herein before described, to swing or move the detent carrier through the arm 46 into a forward position. It will be noted that the lugs or actuators 69 and 71 are arranged to act successively, first upon the wire 54 to release the feeler and trip the latch, and after a predetermined number of picks to then act upon the wire 57 to move the detent carrier and detent to a forward position when the feeler has been engaged by the detent. Obviously, the actuators 69 and 71 may be adjusted relatively to thereby determine the interval that shall elapse between the movement of the feeler to active position and the subsequent movement of the detent carrier to forward position. Thus, should the feeler fail to engage the detent on the first detecting beat during any active period of the feeler, the detent carrier will remain in rearward position until an interval of succession in the operation of the actuators 69 and 71 has permitted the feeler to be moved forwardly a number of times to insure its engagement by the detent. This

is an important feature of the present invention.

tion, because should the feeler not be engaged by the detent when it is moved frontwardly by a working supply of filling on a detecting beat, the detent carrier waits a predetermined interval for another try of the feeler for engagement with the detent before the detent carrier is moved frontwardly, thereby practically insuring engagement between the feeler and detent before 10 the detent carrier moves to withdraw the feeler beyond the reach of the filing.

What is claimed is:

1. In an intermittent feeler mechanism for looms, the combination of a feeler, a device 15 for engaging and holding the feeler in a frontward position during periods of inactivity, and two independent control mechanisms for said device, one operating independently of the other for freeing the feeler 20 at intervals and for moving said device frontwardly when again engaged by the feeler, and independent means located at a pronounced distance from the feeler mechanism and actuated by a going part of the 25 loom for positively actuating said two independent mechanisms in succession.

2. In a feeler mechanism for looms, the combination of a feeler, a detent for holding the feeler in a frontward position during 30 periods of inactivity, a detent carrier pivotally mounted to swing on a vertical axis towards and from the front of the loom, a pivoted latch for holding the detent carrier in a frontward position when engaged by the feeler, a trip for freeing the feeler 35 from the detent at intervals and disengaging the latch from the detent carrier.

3. In a feeler mechanism for looms, the combination of a feeler, a device for holding the feeler in a frontward position during 40 periods of inactivity, controlling mechanism for freeing the feeler from said device, a second controlling mechanism for moving the device frontwardly when engaged by the 45 feeler, means for operating the first controlling mechanism to free the feeler at intervals, means operating independently of the first-named means for causing the second controlling mechanism to withdraw the 50 feeler frontwardly when again engaged by said device, and each of said means being actuated by mechanism supported independently of and remote from the mechanism associated with the feeler.

4. In a feeler mechanism for looms, the combination of a feeler, a detent carrier pivotally supported to swing towards and from the front of the loom, a detent pivotally mounted on the detent carrier, an arm 55 for swinging the detent carrier frontwardly to cause the detent to move the feeler to a frontward position, a latch for holding the detent carrier in its frontward position, means for actuating the detent to free the feeler at intervals and trip the latch to per-

mit rearward movement of the detent carrier.

5. In a feeler mechanism for looms, the combination of a feeler, a detent carrier mounted for movement towards and from the front of the loom, a detent movably mounted on the detent carrier, a latch for locking the detent carrier in its frontward position and having a part overlying the detent, an arm for moving the detent carrier and detent frontwardly to the latch locking position, means for moving the detent to release the feeler and trip the latch, and separate means for operating said arm to move the detent carrier and detent front- 80

wardly. 6. In a feeler mechanism for looms, the combination of a feeler, a detent for holding the feeler in a frontward position, a trip mechanism for freeing the feeler at intervals, a detent carrier, and means, independent of the trip mechanism, and actuated from a going part of the loom, not associated with or actuated by the lay for moving the detent carrier frontwardly when the feeler is engaged by the detent.

7. In a feeler mechanism for looms, the combination of a feeler, a detent for holding the feeler in a frontward position, a trip mechanism for freeing the feeler at intervals, a detent carrier mounted for swinging movement about a fixed pivot towards and from the front of the loom, mechanism independent of the trip mechanism for swinging the detent carrier frontwardly, and means for operating the independent mechanism after a plurality of movements of the feeler, by a working supply of filling in the shuttle.

8. In a feeler mechanism for looms, the combination of a feeler, a detent carrier supported for rocking movement, a detent mounted on the detent carrier and constructed to hold the feeler in a frontward position, a rocking lever movable independently of the detent carrier and adapted to be rocked against a portion of the carrier to force the latter to its frontward position, means for periodically actuating the detent to release the feeler, and means for actuating said lever to retract the feeler.

9. In a feeler mechanism for looms, the combination of a feeler, a detent for holding the feeler in a frontward position during periods of inactivity, a latch for holding the detent during inactive periods of the feeler, and a trip mechanism for freeing the feeler from the detent and tripping the latch, means for swinging the detent rearwardly to again engage the feeler when the latch is tripped, and means actuated by mechanism not associated with the feeler for swinging the detent frontwardly when engaged by the feeler.

10. In a feeler mechanism for looms, the

combination of a feeler, two independently operating mechanisms for controlling the active and inactive periods of the feeler, means actuated by a part of the driving 5 mechanism for the take-up for operating said mechanisms in succession, and means for varying relatively the interval between the successive operations of said mechanisms.

11. In a feeler mechanism for looms, the 10 combination of a feeler, a detent carrier mounted for swinging movement about a vertical axis, a detent mounted on the detent carrier for movement about a horizontal axis to engage and release the feeler, a latch for 15 holding the detent carrier in a frontward position, and a trip for freeing the detent

from the feeler and the latch from holding engagement with the detent carrier.

12. A feeler mechanism for looms, comprising, in combination, a feeler, a detent 20 carrier mounted for movement about a vertical axis at one side of the feeler, a latch for holding the detent carrier in a frontward position, a detent mounted on the detent carrier, a trip for freeing the feeler 25 from the detent at intervals and for tripping the latch, and means for swinging the detent carrier frontwardly after the feeler has been engaged by the detent.

In testimony whereof I have signed my 30 name to this specification.

HARRY A. DAVIS.
